FIG. 5. 21

INVENTOR
Joseph A. Barry
BY
J. S. Preewer
ATTORNEY.

UNITED STATES PATENT OFFICE.

JOSEPH A. BARRY, OF PHILADELPHIA, PENNSYLVANIA.

SPOTTING DEVICE FOR THE TENPINS OF BOWLING ALLEYS.

Application filed February 12, 1923. Serial No. 618,460.

This invention relates to bowling alleys, such as are adapted for spacing a number of pins, usually ten, at one end of the alley to be knocked down by a shot thrown by a

5 player at the opposite end.

In a game of this character the object of the player is to cause all the pins to be knocked down at one throw of the shot, the shot being aimed at a particular pin in such 10 a manner that the pin knocked down by the shot will strike an adjacent pin, which in its turn will strike a third pin, etc. In order to make the game depend upon the skill and experience of a player, the pins should have 15 relatively fixed positions.

A well known method of fixing the relative positions of the pins is to provide the alley bed with vertical holes through which are projected spotters. The pins are then 20 mounted on the spotters and the spotters are then withdrawn from under the pins.

One of the principal objects of my invention is to produce a spotter which could be easily withdrawn and which will not get 25 stuck.

A further object is to provide improved means for projecting the spotters upwardly of the bed.

A still further object is to provide improved means normally adapted to withdraw the spotters from under the pins.

A still further object is to provide improved means for mounting and replacing the spotters.

35 A still further object is to provide an improved spotting apparatus for a bowling alley.

With the above and related objects in view this invention comprises the construction, combination and arrangement of parts hereinafter described, an embodiment whereof is illustrated in the accompanying drawing, and is embraced within the scope of the appended claims.

45 In the said drawing:—

Fig. 1 is a plan of a portion of a bowling alley provided with my improved spotting apparatus.

Fig. 2 is an enlarged horizontal section 50 thereof.

Fig. 3 is an enlarged portion of Fig. 2.

Fig. 4 is an enlarged portion of Fig. 2 showing the position of the spotters when the pins are being mounted.

Fig. 5 is a plan of a split washer for holding the spotters.

Referring more particularly to the drawing for a detail description of my invention, 6 represents a bowling alley provided with a bed 7. The bed is provided vertically 60 with countersunk holes for the flanges of conical sockets 8 attached to the bed by screws, as shown in Fig. 4.

Underneath the bed is mounted a rectangular frame 9, provided at each corner with 65 a hole for a rod 10 carried by a head provided with a flange 11, joined with the bed by screws, as shown in Fig. 3. The lower free ends of the rods are projected through the holes at the corners of the frame 9, the 70 projected portions being provided with threads for nuts 12. Upon the floor 13, underneath the alley, are mounted rods 14 having their upper free ends extended inside the nuts 12 and in alignment with the rods 10, 75 there being a gap left between the rods which is bridged by the nuts.

The rods 10 carry springs 16 which are normally adapted to force the frame 9 downwardly upon the nuts 12. The frame is provided transversely with bars 17 which are provided with seats or recesses for the heels 18 of the conical spotters 20. Split washers 21 fastened to the frame are adapted to engage the spotters above the heels and to hold 85 them firmly to their seats. The spotters are beveled or cone shaped, being of lesser diameter at the top than at the heel.

Attached to the bed thereunder are brackets 22 provided with a pin 23, which serves 90 as a fulcrum for a lever of the first class 24. One of the arms of the lever is in position to be reached from the rear of the alley and the opposite arm is in engagement with a bracket 25 carried by the frame 9 centrally 95 thereunder, said bracket being provided with a slot having cams above and beneath the operating end of the arm.

To place the pins 26 in their proper relative positions, an attendant presses down 100

upon the free arm of the lever 24 causing the arm engaged with the cam to swing upwardly forcing the frame 9 upwardly until the spotters 20 are projected through the sockets 5 from the positions shown in Fig. 2 to that shown in Fig. 4. The attendant then places the pins 26 which, as shown in Fig. 4, are provided with recessed bottoms, over the spotters. When all the pins have thus been 10 placed, the lever is released and the springs 16 force the frame downwardly upon the nuts 12, withdrawing the spotters from under the pins, until the tops of the spotters are just below the top surface of the bed. 15 To prevent the displacement of the pins during the withdrawal of the spotters, the frame must be made to move along straight lines perpendicular to the bed and since the frame is moved downwardly when the 20 springs expand, the expansion of the springs 16 along straight lines is secured by the bolts 10.

The object of making the spotters cone shaped or beveled is to prevent them from 25 getting stuck in the sockets. To replace a worn spotter, the split washers permit of the easy and quick withdrawal and the substitution of another spotter. The arrangement of the rods 10 and 14 and nuts 12 30 provides a convenient way for the replacement of worn or broken springs 16. Normally the frame 9 rests upon the nuts 12 which are held in position by the cutter pins 27 of the rods 14 provided transversely 35 with perforations for the pins. When the pins are pulled out and the nuts removed from the rods 10, said nuts 12 slide down the rods 14, permitting the frame 9 to slide downwardly until the gaps between the rods 40 10 and 14 are above the frame when any of the springs may be removed from its rod and passed through the gap and a new spring substituted. The frame may then be forced upwardly by the lever; the nuts 45 mounted on the rods 10 and the cutter pins inserted in the perforations of the rods 27. The cam of the bracket 25 is adapted to convert the curvilinear movement of the lever 24 into a straight up and down movement of the frame 9.

What I claim is:—

1. In combination with the bed of a bowling alley provided with vertical openings, spotters movable vertically in said openings, said openings being surrounded by conical surfaces and said spotters having corresponding conical surfaces to facilitate the movement of the spotters outwardly of the openings.
2. The combination claimed in claim 1, including a movably supported frame under the bed carrying the spotters in alinement with the openings.
3. A bowling alley comprising a bed provided vertically with conical openings, a

frame thereunder provided with conical spotters, said frame provided with seats for the spotters, a split spring washer mounted over each seat, said seats adapted to support the spotters vertically in alinement with the openings. 70

4. The combination claimed in claim 3, said spotters provided with heels engaged by said springs.

5. In combination with the bed of a bowling alley provided with vertical openings, a movably supported frame thereunder provided with spotters registering with the bed openings, rods suspended from the bed and projected through the frame adapted to 75 guide it vertically, and coil springs mounted on said rods to control the movement of the frame. 80

6. The combination claimed in claim 5, and adjustable means suspended from the rods beneath the frame adapted to limit its 85 downward movement.

7. In a bowling alley, the combination of a bed provided with vertical openings, a frame thereunder provided with spotters 90 registering with said openings, and means for moving the frame to project the spotters through the openings comprising a lever, a bracket suspended from the frame provided with slot for the frame operating arm of the 95 lever, said slot provided with cams above and below the operating end of the arm to cause the frame to move vertically.

8. The combination claimed in claim 7, and a bracket suspended from the bed provided with a fulcrum for the lever. 100

9. In a bowling alley, the combination of a bed provided with openings for the positioning of the bowling pins, a frame thereunder provided with spotters in alinement with the openings, rods suspended from the bed and projected through the frame, means mounted on said rods adapted to move the frame downwardly, pedestal rods in alinement with said suspended rods, the tops and bottoms of the respective rods being spaced apart and nuts bridging said spaces. 105 110

10. The combination claimed in claim 9, and means removably connected with said pedestal rods adapted, when disconnected, 115 to permit the nuts and frame to descend.

11. In a bowling alley, the combination of a plurality of bowling pins having tapered recesses, a floor having a plurality of tapered holes therein, a tapered centering pin 120 for each of the tapered holes in the floor, and means for moving the tapered centering pin into engagement with a recess in a bowling pin to accurately position the bowling pin. 125

12. In a bowling alley, the combination of a plurality of bowling pins, a floor having a plurality of tapered holes therein, a tapered centering pin for each of the tapered holes in the floor, means for moving the tapered centering pin into engagement with

the bowling pin to accurately center the bowling pin, and yielding means for retracting the centering pins from the positions wherein they engage the bowling pins.

5 13. In a bowling alley, the combination of a plurality of bowling pins having tapered recesses, a floor having a plurality of

tapered holes therein, a tapered centering pin for each of said holes, said tapered pin adapted to snugly fit said hole and said recess when said pin is placed on said floor.

In witness whereof I have signed this specification.

JOSEPH A. BARRY.
